UNITED STATES PATENT OFFICE.

JOSEPH WILLIAM DROLL, OF CHICAGO, ILLINOIS, ASSIGNOR TO DROLL PATENTS CORPORATION, OF CHICAGO, ILLINOIS, A CORPORATION OF DELAWARE.

MATTRESS-BEATING MACHINE.

Application filed August 17, 1926, Serial No. 129,799. Renewed July 9, 1928.

My invention relates to improvements in mattress beating machines wherein a solid rotatable and slidable mattress support within an open end housing operates in conjunction with an inhalant element and a plurality of beating elements adjustably and pivotally mounted above said support to beat the stuffing from the center of a mattress toward the edges and corners thereof and to confine the dust beaten from said mattress during the beating operation.

The primary object of the present invention is to provide a new and improved mattress beating machine.

Another object of the present invention is to provide a new and improved device of the character described having improved means for beating the stuffing of a mattress from the center into the edges and corners thereof.

A further object of the present invention is to provide a rigid or solid support arranged to effectively hold the mattress against the beating action of the beating elements thereby providing a more effective beating process or action.

A still further object is to provide a rotatable rigid support whereby a mattress may be turned to expose every portion of the upper surface thereof to the action of the beating elements.

Another object is to provide an improved mattress beating machine having a closed housing, open at one end, to enclose a plurality of beating elements operating in conjunction with a rigid mattress support slidable into and out of said housing through the open end thereof to confine dust liberated from said mattress during the beating process, together with an inhalant element arranged to inhale said dust from said housing, to a remote point.

Another object of the invention is to provide improved means for stripping the mattress from the beating elements during the beating process.

I accomplish these and other objects by means of the improved device disclosed in the drawings forming a part of the present application wherein like characters of reference are used to designate similar parts through the specifications and drawings, and in which—

Fig. 1 is a broken front elevation of my improved mattress beating machine;

Fig. 2 is a broken plan view of Fig. 1; 55

Fig. 3 is a broken end elevation of the right hand end of Fig. 1;

Fig. 4 is a transverse vertical sectional view taken through the housing, beating elements and the rigid or solid mattress support, disclosing the working of the beating machine; 60 and

Fig. 5 is an enlarged broken view of the beating elements and operating mechanism therefor and the solid mattress support beneath. 65

Referring to the drawings the numeral 1 is used to designate a main frame composed of a pair of longitudinally disposed beams from which rises a crane-like superstructure 2 having rotatably mounted thereon a transverse shaft 3 which pivotally supports a walking-beam 4 at its approximate center. One end of the walking-beam 4 is connected by means of suitable links 6 to a nut 7 mounted upon a vertically disposed threaded rod 8 rotatably mounted within suitable bearings 9 on the superstructure 2, which shaft 8 is arranged to be rotated in opposite directions in a manner and for a purpose hereinafter 70 more fully set forth. 75

The opposite end of the walking-beam 4 is provided with bearings 11 which pivotally engage the approximate center portions of bifurcated links 12 and to the lower ends of said bifurcated links 12 is pivotally suspended a cradle 14 within which cradle 14 are pivotally mounted the beating elements and operating mechanism therefor which will herein- 80 after be more fully described. 85

Directly below the cradle 14 and arranged transversely on the beams 1, as disclosed in Fig. 4 of the drawings, I have provided a pair of parallel supporting rails 16 upon which ride rollers 17 in turn supporting a frame 18, whereby said frame 18 may traverse the rails 16, the movement of said frame 18 being limited in either direction by means of suitable stops rigidly secured to the rails 16 and the frame 18. The frame 18 has pivotally 90 mounted thereon, so as to be rotatable, what I term a rigid or solid mattress support 21 supported by suitable rollers 22 and held in central position by means of a suitable king-bolt or pin 23. I use the term "solid" or 95 "rigid" in connection with the mattress support 21 in contradistinction to the flexible mattress support 23 disclosed in my prior 100 105

Patent No. 1,503,352 issued July 29th, 1924 for the reason that I have found from actual experience in building the type of machine set forth in the present specification that a solid or unyielding mattress support in conjunction with the beating elements will not beat a mattress as efficiently as the present rigid or solid support, which support 21, in the present instance, may be composed of rigid or solid planks in the form of a turn-table, and preferably round, as shown.

Immediately above the mattress support 21, then, is the cradle 14 within which cradle 14 are rotatably mounted a plurality of countershafts 26 extending beyond the sides of said cradle 14, which cradle is U-shaped in cross section as disclosed in Fig. 1 of the drawings.

In Figs. 4 and 5 of the drawings I have removed the near side of the cradle 14 for the purpose of disclosing the diverging beating arms 27 rigidly secured to the outer and opposite ends of the countershafts 26 and the operating mechanism for said beating arms 25 27.

The beating arms 27 are preferably arranged in four pairs, that is to say a pair of inwardly extending inner beating arms arranged above and adjacent the center of the mattress support 21 and also a pair of inwardly extending outer beating arms arranged above and adjacent the edges of the mattress support 21, the purpose of which arrangement will hereinafter be more fully described.

Rigidly secured to each pair of heating arms 27 is a transversely arranged beating element or stick 28 formed preferably of hard wood. Secured to each countershaft 26 and arranged within the cradle 14 is a rocker arm 29, and to the rocker arms 29 of the outer beating elements are connected inwardly extending connecting rods 31 which connect at their inner ends with opposite ends of an oscillator 32 having bearing surfaces 33 offset 45 set from each other and actuated by two separate cams 34 mounted upon a shaft 36 in turn rotatably mounted within the cradle 14, as disclosed in Fig. 5 of the drawings.

Similarly two connecting rods 31 extend inwardly from the rocker arms 29 of the inner beating elements and have their inner ends connected to a second oscillator 32 arranged alongside the first oscillator 32, and likewise having two bearing surfaces offset in 55 two planes to engage a second set of cams 34 on the shaft 36, the only difference between the inner and outer beating element connections is that the two cams for the oscillator of the inner beating elements is set slightly in advance of the cams for the outer beating elements in order that said inner beating elements shall be operated slightly in advance of the outer beating elements and thereby strike, or engage, and beat the central portion of a mattress slightly in advance of

the outer beating elements, thereby forcing or beating the stuffing of said mattress from the center toward the outer edges and corners thereof. The two oscillators 32 are pivotally mounted upon a countershaft, and alongside each other as disclosed in Fig. 2 of the drawings.

The countershaft 36 upon which the two sets of cams 34 are mounted, extends beyond one side of the cradle 14 and is provided with a universal joint 41 to which one end of a shaft 42 is feathered, the other end of said shaft 42 being connected through a second universal joint 43 to a suitable clutch 44 as disclosed in Figs. 1 and 2 of the drawings, said clutch 44 being actuated, in the usual manner, to engage and disengage a power shaft 46 by means of a suitable shifting lever 47.

The power shaft 46 is provided with a bevel gear 51 meshing with similar gears 52 and 53 rotatably mounted upon the shaft 8 and each having clutch portions 54 and 55 respectively arranged to be engaged by corresponding clutch members 56 and 57 respectively, feathered on the shaft 8. The clutch members 56 and 57 are actuated by means of a shifting rod 59 in turn actuated by a shifting lever 61, by means of which either or neither bevel gear 52 or 53 may be connected to the shaft 8 whereby said shaft may be rotated in either direction to move the nut 7 on the threaded portion of the shaft 8 to raise or lower the cradle 14 and beating elements mounted therein relatively to the solid mattress support 21 to adjust said beating elements to a mattress on said table, or whereby said nut 7 may be held stationary to retain said adjustment when obtained, said nut 7 being connected to the end of the walking-beam 4 by suitable connecting links 6 as disclosed in Figs. 1 and 3 of the drawings.

The cradle 14 is provided with a framework 63 provided with rollers 64 around which are mounted resiliently held longitudinal and transverse stripping elements 66, said stripping elements or strippers being mounted between the beating elements and a mattress 67 supported by the solid mattress support 21 in order that the upper ticking of the mattress 67 will not follow the upward movement of the beating elements but will be stripped or separated therefrom to permit a more effective beating of said mattress.

The mattress support 21 is surrounded by a closed housing 68 the upper or top portion 69 of which is carried by the cradle 14 and is positioned above the beating elements and strippers 66 as disclosed in Fig. 1 of the drawings. The front end of said housing 68 is opened to permit the passage into and out of said housing of the mattress support 21.

As the top portion 69 of the housing 68 is secured to and movable vertically with the cradle 14, in order to effectively enclose the

solid support 21 and mattress 67 during the beating process, I have provided flexible connections 70 of canvas or other suitable material between the side and rear edges of the top 69 and the upper edges of the sides of the housing 68. By means of this arrangement the mattress is at all times enclosed during the beating process in order to confine the dust beaten out of the mattress during such 10 beating process, and the cradle 14 and beating elements mounted thereon may be raised and lowered without disturbing or disconnecting the enclosure.

In order to remove the dust from the enclosure I have provided an inhalant element which consists of nozzles 71 extending downwardly from a suction pipe 72 carried by the frame 63. The nozzles 71 are preferably arranged directly above the opening in the front end of the housing 68 as the dust has a tendency to rise, and by said nozzles 71 said dust is inhaled as it emerges from the opening in the front end of the housing 68. The suction pipe is provided with a downwardly extending extension 73 which telescopes within a main suction pipe 74 which carries the inhaled dust to a point remote from the machine. By means of this arrangement dust beaten from the mattress is prevented from 20 circulating through the atmosphere of the factory, and therefore a cleaner working atmosphere is provided for operators therein.

In operation the mattress support 21 is moved on its rollers 17 and tracks 16 through 35 the opening in the front of the housing 68 and a mattress 67 to be beaten is placed thereon. The mattress support 21 is then moved back into the housing 68 and under the approximate center of the cradle 14 and 40 beating elements or sticks 28.

By means of a shifting lever 61 one of the clutch members 56 or 57 is moved into engagement with its respective gear 52 or 53 to rotate the threaded shaft 8 in either direction to raise or lower the nut 7, actuate the walking-beam 4 and thereby raise or lower the cradle 14 and the beating elements mounted therein to adjust the said beating elements relatively to the upper surface of the mattress 67. When the proper adjustment has been attained the shifting lever 77 is again actuated to release the shaft 8 from its actuating gear, and by reason of the threaded nut arrangement on said shaft 8 the said beating 55 elements are retained in such adjustment until such time as it is to be changed.

By operating the clutch lever 47 the shaft 42, which operates the countershaft 36 carrying the cams 34, is connected to the power shaft 46 and the cams 34 are then rotated, which rotation causes the two cams 34 for each oscillator 32 thereby operating the connecting rods 31, rocker arms 29, beater arms 27 and the beating sticks 28. As hereinbefore 60 described the cams 34 for the inner beating

elements are actuated slightly in advance of the cams for the outer beating elements, by means of which arrangement the inner beating sticks 28 above and adjacent the approximate center of the upper surface of the mattress 67 on the mattress support 21 engage the upper surface of the mattress 67 and beat the stuffing within the center portion of said mattress toward the outer portion thereof and immediately thereafter the outer beating 70 elements similarly engage said mattress and beat the stuffing which was worked outwardly by the previous stroke of the inner beating elements and by continued beating of the inner and outer beating elements, said stuffing 75 is beaten effectively outwardly from the center of said mattress.

By moving the mattress support 21 inwardly and outwardly on its tracks and also by rotating said mattress support 21 during 80 such beating process it is obvious that every portion of the mattress may be exposed to the action of the beating elements and the result is a very effective beating of the mattress to provide a uniform distribution of 85 the stuffing throughout said mattress as well as into the edges and corners thereof.

The dust beaten from the mattress during the beating operation is inhaled through the nozzles 71 and carried to a point remote from 90 the machine to prevent circulation of said dust throughout the atmosphere of the factory.

The compensating links 81 pivotally connected to the frame 2 and the upper ends of the bifurcated links 12, and the connecting links 82 connected at their lower ends to one side of the frame 63 of the cradle 14 and at their upper ends to the auxiliary walking-beam 83 which is in turn connected to the 100 walking-beam 4, are provided in order to retain the cradle 14 and the beating elements at all times in a horizontal position and as they form no part of the present invention I have not entered into a detailed description 105 of their operation.

Having thus described my invention what I claim as new and desire to secure by Letters Patent is:

1. A mattress beating machine comprising 115 a solid mattress support; a plurality of inner and outer beating elements pivotally mounted above the center and edges of said support respectively; and means for operating the inner beating elements slightly in advance of the outer beating elements to engage and beat a mattress upon said support and thereby beat the stuffing of said mattress from the center toward the edges thereof.

2. A mattress beating machine comprising 125 a rotatably mounted solid mattress support; a plurality of inner and outer beating elements pivotally mounted above the center and edges of said support respectively; and means for operating the inner beating ele- 130

ments slightly in advance of the outer beating elements to engage and beat a mattress upon said support while the same is being rotated to beat the stuffing of said mattress from the center toward the edges and corners thereof.

3. The combination with a mattress beating machine, of inner and outer beating elements arranged to engage and beat the central and outer portions of a mattress respectively; and means for actuating the inner beating elements slightly in advance of the outer beating elements to beat the stuffing from the center of a mattress toward the outer portions thereof.

4. The combination with a mattress beating machine, of inner and outer beating elements arranged to engage and beat the central and outer portions of a mattress respectively; a mattress support, and stripping elements arranged between the mattress and the beating elements to separate said mattress from said beating elements.

5. The combination with a mattress beating machine, of inner and outer beating elements arranged to engage and beat the central and outer portions of a mattress respectively; a mattress support; and resiliently mounted stripping elements arranged between the mattress and said beating elements to separate said mattress and said beating elements.

6. A mattress beating machine comprising a solid horizontally disposed mattress support; a plurality of beating elements pivotally mounted above said support; means for raising and lowering said beating elements relatively to said support; means for actuating said beating elements to engage and beat a mattress on said support; and stripping elements arranged between said mattress and said supports to separate the same.

7. A mattress beating machine comprising a solid horizontally disposed mattress support; a plurality of beating elements pivotally mounted above said support; means for raising and lowering said beating elements relatively to said supports whereby the force of a blow delivered by said beating elements to said mattress may be regulated and adjusted; means for actuating said beating elements to engage and beat said mattress; and resiliently mounted stripping elements arranged to be raised and lowered with said beating elements and to separate said mattress from said beating elements.

8. The combination with a mattress beating machine of a solid mattress support pivotally mounted to rotate within a horizontal plane; a plurality of inner and outer beating elements pivotally mounted above and adjacent the center and outer edges of said support; means for raising and lowering said beating elements relatively to said support to adjust and regulate the force of a blow

from said beating elements to a mattress on said support; means for operating the inner beating elements in advance of the outer elements to engage and beat said mattress while said support is being rotated whereby the stuffing of said mattress may be beaten from the center toward the edges and corners thereof; and stripping elements mounted between a mattress on said support and the beating elements.

9. The combination with a mattress beating machine of a solid mattress support pivotally mounted to rotate within a horizontal plane; a plurality of inner and outer beating elements pivotally mounted above and adjacent the center and outer edges of said support; means for raising and lowering said beating elements relatively to said support to adjust and regulate the force of a blow from said beating elements to a mattress on said support; means for operating the inner beating elements in advance of the outer elements to engage and beat said mattress while said support is being rotated whereby the stuffing of said mattress may be beaten from the center toward the edges and corners thereof; and resiliently mounted lateral and longitudinal stripping elements mounted between a mattress on said support and said beating elements.

10. A mattress beating machine comprising a housing open at the front end thereof; a solid mattress support slidably mounted for movement into and out of said housing through said opening; a plurality of beating elements arranged above said mattress support; means for actuating the beating elements to engage and beat a mattress on said support; and an inhalant element arranged adjacent the opening in said housing to inhale dust beaten from said mattress.

11. A mattress beating machine comprising a housing open at one end thereof; a solid mattress support slidably mounted for movement into and out of said housing through said opening; a plurality of inner and outer beating elements arranged above and adjacent the center and edges of said support; means for operating the inner beating elements in advance of the outer beating elements to engage and beat the stuffing of a mattress on said support from the center toward the edges of said mattress; and an inhalant element mounted adjacent the opening in said housing to inhale from said housing dust beaten from said mattress.

12. A mattress beating machine comprising a rigid horizontally disposed mattress support; a plurality of beating elements arranged above said support; means for raising and lowering the beating elements to adjust said beating elements relatively to a mattress on said support; a housing enclosing said support and having an open end and a top portion secured above said beating ele

ments and arranged to be raised and lowered therewith; means for actuating the beating elements to engage and beat a mattress on said support; and an inhalant element mounted adjacent the opening in said housing to inhale dust beaten from said mattress.

13. The combination with a mattress beating machine of a rigid horizontally disposed rotatably mounted mattress support; a plurality of inner and outer beating elements pivotally mounted above and adjacent the central portion and edges of said support; means for raising and lowering the beating elements to adjust the same relatively to a mattress on said support; a housing having an open end and enclosing said support, the top of said housing being arranged above and secured to said beating elements and movable vertically therewith; flexible connections between the edges of said top of the housing and the housing; means for actuating the inner beating elements in advance of the outer beating elements to engage and beat a mattress on said support to beat the stuffing from the center of said mattress toward the edges thereof; and an inhalant element mounted adjacent the opening in the housing to inhale from said housing dust beaten from said mattress.

14. The combination with a mattress beat-

ing machine of a rigid horizontally disposed rotatably mounted mattress support; a plurality of inner and outer beating elements pivotally mounted above and adjacent the central portion and edges of said support; means for raising and lowering the beating elements to adjust the same relatively to a mattress on said support; a housing having an open end and enclosing said support, the top of said housing being arranged above and secured to said beating elements and movable vertically therewith; flexible connections between the edges of said top of the housing and the housing; means for actuating the inner beating elements in advance of the outer beating elements to engage and beat a mattress on said support to beat the stuffing from the center of said mattress toward the edges thereof; an inhalant element mounted adjacent the opening in the housing to inhale from said housing dust beaten from said mattress; and stripping elements mounted longitudinally and laterally below said beating elements and movable vertically therewith to separate said mattress from said beating elements.

In witness whereof I hereunto set my signature.

JOSEPH WILLIAM DROLL.
